CLAIM

The ornamental design for an exterior shell of a trunk door of a car top carrier, as shown and described.

DESCRIPTION

FIG. 1 is a top plan view of a trunk door for a car top carrier or similar article showing my new design, the fragmentary broken line representation of a car top carrier being only for purposes of illustrating environmental features and forms no part of the claimed design; FIG. 2 is a right side elevational view thereof, the left side elevational view being a mirror image of the view of FIG. 2; and FIG. 3 is a rear elevational view thereof.
